Alexander M. Ostellony

UNITED STATES PATENT OFFICE.

ALEXANDER M. BELLONY, OF THE UNITED STATES ARMY.

CLAMPING MECHANISM.

1,371,545.

Specification of Letters Patent.

Patented Mar. 15, 1921.

Original application filed April 24, 1919, Serial No. 293,031. Divided and this application filed April 26, 1919. Serial No. 293,029.

(FILED UNDER THE ACT OF MARCH 3, 1883, 22 STAT. L., 625.)

To all whom it may concern:

Be it known that I, ALEXANDER M. BELLONY, captain, corps of engineers, United States Army, a citizen of the United States, 5 stationed at Washington, District of Columbia, have invented an Improvement in Clamping Mechanism, of which the following is a specification.

The invention described herein may be 10 used by the Government, or any of its officers or employees in prosecution of work for the Government, or by any other person in the United States, without payment of any royalty thereon.

15 This invention relates to a novel clamping mechanism which, while designed more particularly for use in connection with pile-driving machines, is applicable for use in other situations; and the present application 20 covering this invention is a divisional application of a parent application filed April 24, 1919 Serial No. 293,031, and is a companion case to an application filed April 26, 1919, Serial No. 293,028 embodying 25 somewhat similar subject-matter.

The object of the invention is to provide a novel clamping mechanism which is extremely simple in construction, very easy to operate, thoroughly efficient in operation, 30 and durable in use.

With this object in view, and others appearing as the specification proceeds and the nature of the invention more fully develops, the invention resides in a type of 35 clamping mechanism controllable from the bottom of a pile-driving machine, or other object in connection with which it is used.

The invention is graphically illustrated in the accompanying drawing, in which like 40 reference characters designate corresponding parts throughout the several views. The views comprising the drawings may be briefly described as follows:

Figure 1 is a view in side elevation of my 45 clamping mechanism, showing the application of the clamping mechanism to a portion of the pile-driving machine, shown partly in section:

Fig. 2 is a view in front elevation thereof.

50 Fig. 3 is a detail view, partly in section, of the screw, screw-nut and clamp-seat;

Fig. 4 is a top plan view of the clamp-seat.

Referring, now, in detail to the drawing:

A clamping dog 1, is pivotally supported 55 on a pivot pin 2 projecting through depend-

ing ears 3, 3 of a bracket 4, adapted to be secured, as by rivets 5, 5, to a support A, in this instance a channel on the upper frame of a pile-driving machine. The pivot pin passes through a transverse slot 1^a in the 60 dog 1, forming a lost-motion connection. The dog 1 carries, at the end thereof opposite the pivotal point, an arm 6, through which is threaded a clamp screw 7 provided with a head 8 seated in a screw nut 9. This 65 nut is preferably hexagonal in shape and is tapped at its upper end for the reception of a clamp seat 10, having a threaded stem 11 adapted to be screwed into the screw nut 9 and into proximity with the head 8. A 70 crank 12 is secured to the end of the screw 7. In operation, it will be understood that, by rotating the crank 12, the clamp screw 7 will be raised or lowered, thus raising or 75 lowering the nut 9 and the seat 10, so that the latter is brought into or out of contact with the channel B of the lower frame of a pile-driving machine, or the like.

It will be noted that the clamp seat 10 is 80 rectangular in form and longitudinally grooved, as shown at 13, so as to fit the bottom flange of the channel B. Due to this peculiar construction of the clamp seat, the clamp can be used even though, as in this case, the lower channel B to be clamped is 85 not in parallel relation with the upper channel A, to which the bracket 4 is secured. This use is further facilitated by the lost-motion connection of the clamping-dog 1 on its pivot-pin 2, since limited horizontal adjustment is permitted thereby. 90

It will be noted that this type of mechanism is controllable from the bottom of the pile-driving machine instead of from the top, as in the companion form of clamping 95 mechanism disclosed in my copending application filed April 26, 1919, Serial No. 293,028.

Having thus fully described my invention, what I claim as new is:

1. The combination with a transportable 100 structure and a rail for supporting said structure, of a clamping dog pivoted to the structure, a clamp screw threaded through said dog, a screw nut carried by said clamp screw and a clamp seat detachably carried by said screw nut. 105

2. The combination with a transportable structure and a rail for supporting said structure, of a clamping dog carried by the 110

- structure, a clamping screw threaded through said dog, a screw nut swiveled on said clamping screw and a clamp seat detachably carried by said screw nut.
- 5 3. The combination with a transportable structure and a rail for supporting said structure, of a bracket carried by the structure, a pivot pin carried by said bracket, a clamping dog having a lost motion connection with said pivot pin, a clamp screw threaded through said dog, a screw nut car-
- 10

ried by said clamping screw and a clamp seat detachably carried by said screw nut.

4. The combination with a transportable structure and a rail for supporting said structure, of a clamping dog carried by said structure, a clamp screw threaded through said dog, a screw nut carried by said clamp screw and a clamp seat having an elongated grooved head and a screw stem threaded into 15 said screw nut.

ALEXANDER M. BELLONY.
